UNITED STATES PATENT OFFICE.

IRONE H. RUSSELL, OF WASHINGTON, DISTRICT OF COLUMBIA.

AMBULANCE.

No. 910,728.

Specification of Letters Patent.

Patented Jan. 26, 1909.

Application filed May 28, 1907. Serial No. 376,173.

To all whom it may concern:

Be it known that I, IRONE H. RUSSELL, a citizen of the United States, residing at Washington, in the District of Columbia, 5 have invented certain new and useful Improvements in Ambulances; and I do hereby declare the following to be a full, clear, and exact description of the invention, such as will enable others skilled in the art to which 10 it appertains to make and use the same.

My present invention pertains to the class of ambulances or wheeled litters, for use in the handling of the sick and injured.

It has for its object in part, the supplying 15 of an efficient wheeled transport and one in which the wheels can be easily and readily detached when it is desired to use the same as a hand litter.

The other objects of my invention will 20 readily appear from the accompanying drawings in which the best form in which I have contemplated embodying my invention is illustrated, and from the following description and claims in which my said invention is 25 disclosed.

In the drawings, Figure 1 is a longitudinal section of my improved ambulance or wheeled litter. Fig. 2 is a top or plan view. Fig. 3 is a transverse sectional view. Figs. 4, 5 30 and 6 are views of details of construction. Fig. 7 is a top or plan view of the stretcher frame, with patient supporting and holding attachments. Fig. 8 is a view of the device with the wheels in their highest position. Fig. 9 is a view of one of the clamps for attaching the wheels to the frame. Fig. 10 is 35 a view showing means for holding screen frames in position. Fig. 11 is a detail showing method of attaching the supporting and 40 retaining bands to the bottom of the stretcher, and Fig. 12 is a side view of padded shoulder strap.

The main body of my litter consists of the frame A which is shown as constructed of 45 tubular materials. It is preferably made as light as is consistent with the requirements of rigidity and strength, but I do not limit myself to a metallic or tubular material.

Within the frame A is a flexible support B 50 for the body of the sick or injured person, which may be of canvas or any other preferred material and this is secured to the frame in the manner that the user or users may choose or prefer. This support does not 55 extend the full length of the frame A but at the ends is secured to cross pieces A' A'.

leaving a space between such cross pieces and the curved frame ends to permit the latter to be grasped by attendants to guide or carry the litter.

60

In order to provide a wheeled support for the litter or stretcher when it is desired, I provide the hinged brackets or clamps a a that can be securely clamped to the side frame bars at the points indicated in the drawings. 65 In this instance, they are shown as being thus secured by the clamping bolts a' a', but other clamping means may be employed if preferred. To these brackets are secured all the parts of the wheeled support. The inner 70 part of each bracket is provided with the two downwardly extending ears a² a³. To each of the ears a³ at one end of the frame is pivoted an arm C that extends towards the center of the frame and has its opposite end rigidly 75 secured to a bracket D. In these brackets is mounted the axle E. The axle may have the wheels F rigidly secured thereto and the axle journaled in the brackets D, or the axle may be rigidly secured in the brackets and the 80 wheels made to revolve thereon as may be preferred.

To the ears a³ at the opposite end of the frame are pivoted arms C' which are each composed of two parts c c', pivoted together 85 at c'. The shorter member is pivoted to the bracket D at d.

The brackets D have each an upwardly extending ear d' to which is pivoted the elbow releasing lever G. To the shorter arm 90 of this lever is pivoted the stirrup g, the bifurcated ends of which extend downward upon each side of the arm C' and through these ends pass the pivot c'. This joint at c' can be made to bend downward but not 95 upward.

In the ears a² at each end of the frame is pivoted a shaft or rod H, to which are secured two legs or supports h h, and springs h' h' are secured to the shaft in such manner that such 100 springs will tend to move the said legs h h into and maintain them in a vertical position. To each of said legs h at a point a short distance from the shaft H is pivoted a link h². The two links at one side of the frame extend 105 downwardly in an inclined direction beneath the axle E and have their opposite ends pivotally connected at d². When the axle is in the position shown in full lines in Fig. 1, the downward pressure of the axle upon the 110 links h² draw the legs inward to the folded position shown in the same figure. When

the levers G are raised and the arms C' are bent or flexed downwardly, the weight of the frame A, and whatever load may be supported thereby, will cause the frame to move downwardly towards the axle. As the springs h' h' tend always to throw the legs outwardly, the legs will be moved outwardly toward a vertical position as fast as the links h² will permit, so that by the time the frame reaches its lowest position, the legs will be in position to engage the ground and sustain the entire weight of the device and its load. The wheels will be relieved from all weight which will be transferred to the supporting legs. In place of the links h² h², the legs on one side of the axle might be connected with the legs on the other side by cords or chains. The links are, however, my preferred construction. In this position, which is shown in Fig. 8, the ambulance or litter will stand firmly and without any care whatever, to receive its load or to have it removed therefrom. As soon as this operation is concluded, the levers will be brought downward and the weight of the frame and its load transferred to the wheels bringing the parts into the position shown in full lines in Fig. 1, in which position it is ready to be pushed or drawn to the point desired. When in the position shown in Fig. 1, the levers are held by hooks g'. The moving of the stretcher frame upward will cause the links to draw the legs into their folded position. There may be cases in which it will be desired to hold the body upon the stretcher from moving or being jarred from the canvas within the frame, or it may be desired to retain the body of the patient, or of the limbs of the same in certain positions. To secure these ends, I employ certain constructions which will now be described.

Along the outer edges of the canvas or flexible supporting material are secured strips b b' several inches in width. The inner corners of these strips are provided with short hooks (not shown). At the outer ends of the bars A' A', sleeves a⁴ are movably mounted upon the said bars. These sleeves are kept in proper position upon the bars by pins a⁵ a⁵ and the said sleeves are provided with shoulders a⁶, that will engage the said pins and the sleeves will be held from further movement. Each of the said sleeves is provided with two ears a⁷ a⁷ between which are pivoted the short arms b⁸ b⁸ having at their outer ends a ring or loop b⁴. When it is desired to utilize the securing strips b b' these arms are turned up to the position shown in Fig. 5, and the hooks of the adjacent corners of the strips b b' are hooked into the ring or loop b⁴ of the arms b⁸ at that place. The strips will then be held elevated to the extent desired and will act as the sides of a wagon body to protect the load. When these strips 65 are not needed, they will lie flat upon the

canvas support or be folded to take up less space thereon, and the arms b⁸ b⁸ will be folded and the sleeves turned to cause the arms to fall below the frame, as seen in Figs. 1 and 8. When it is desired to hold the body 70 of the patient or some part of the same from the possibility of a material degree of movement I provide the following means. At one end the corners are strengthened by an additional thickness of canvas or other material, and to these corners are secured straps B' so that such straps may be placed under the arms of the patient and secured by buckles or other means. When so secured each strap forms a loop as shown in Fig. 12. These 75 straps are preferably provided with rounded padded parts b¹⁰ to engage the armpits of the patient and these pads may be made movable upon the strap by having loops on the ends of the same through which the straps B' 80 pass.

At a convenient point to embrace the body of the patient to a greater or less extent between the shoulders and hips, a stout piece of canvas or other material B² is secured to the 90 supporting canvas B. This securing band B² is secured by two rows of stitching a short distance apart. On the outer side of such bands, when folded are secured stout tapes b⁹, at a sufficient distance from the ends to 95 enable the ends to be overlapped around the patient's body and then be secured by tying the tapes. Instead of tapes, stout webbing and buckles may be employed if preferred. Two other bands B³, B³ of like character are 100 secured to the bottom canvas at each side. These bands are shorter and are made to receive the arms of the patient. Two other such bands B⁴ B⁴ are provided at the proper places for the legs of the patient. By means 105 of these bands the body of the patient can be secured and one or more limbs can be held in the position desired. When not needed, such bands can be opened upon the bottom canvas and will not be materially in the way 110 of using the litter when their use is not desired.

It is often desired to protect the patient from rain or the direct rays of the sun. To accomplish this I provide a canopy I composed of two rigid side frames connected by jointed bars i i at the ends. The joints in bars i i are such as to permit these bars to fold inwardly in the horizontal plane of the top bars of the side frames. The lower bars i 115 at each end are provided with spring clips i' i' which can be forced upon the bars or rods A' A' just inside of the sleeves a⁴. A means for rigidly securing the frame of the canopy to the litter may be employed in 120 place of the spring clips if desired. This canopy frame is provided with a water proof cover permanently secured thereto. The sides are preferably provided with some fine meshed material that will admit the free 125 pass- 130

sage of air therethrough but prevent the admission of flies or other insects. To cover these previous sides, I provide water proof flaps l' that can be lowered to protect the 5 interior of the litter from driving rain, but which can be rolled up and secured or be merely thrown upon the top, see Fig. 3, as may be deemed best. When the canopy is not in use by bending the end pieces inward 10 the sides will be folded together and occupy but little space. In order that the top may not sag and so assume a hollowed condition which would retain the rain falling upon it, I may provide the longitudinally extending 15 bar l^2 . This bar has one end rigidly secured in a socket i^2 pivotally secured to the top end piece at one end of the canopy, and at the other end passes freely through a corresponding socket i^3 on the end piece at the other end 20 of the canopy. In folding the rod or bar will slip through socket i^3 . As this bar is placed above the end pieces and beneath the covering it serves to give the covering the semblance of a roof so that it prevents rain from 25 accumulating upon it.

In order to provide means whereby individual ambulances may be connected when desired, each end of the stretcher frame is provided with a coupling piece. These are 30 shown at J , J' . Each of these couplers or coupling pieces consists of a sleeve loosely mounted on the end piece of the stretcher frame. These sleeves or collars are held in position by two pins, one on each side and 35 each is provided with two shoulders j , j' which engage said pins when the collar is turned upwardly on the outside of the frame until the coupling portions come to a horizontal position. The coupling portions of the coupler 40 J consist of two ears j' , j' a short distance apart extending outwardly from the sleeve or collar. The coupling part of the coupler J' is an ear or tongue j^2 extending from the collar.

To connect two of the ambulances, the tongues j^2 of one ambulance is inserted between the ears j' , j' of another and secured together by a pin j^3 . This pin is secured to one of the coupling parts by a short chain to 50 prevent it from becoming displaced. As the coupling pieces are held by the pins from passing a horizontal position, two ambulances thus connected will be maintained in proper position for transportation.

I may prefer to have the mosquito or insect netting made in sections capable of being inserted between the upright rods forming the side frames of the canopy. These will be provided at one side with two bifurcated 55 clips k , while on the opposite side will be two pivoted slips k' . Each of the outer members of the clips k' will have the outwardly projecting lug k^2 by which the clips can be turned into a vertical position. This construction is shown in Fig. 10, which shows

only the upper half of one of said sections. These sections are placed in position by turning the clips k' into a vertical position. The clips at the opposite side of the section are then made to engage one of the uprights. 70 The other side of the section is pressed into a like relative position and the clips k' turned downward to engage the upright at that side of the section. A small pin k^3 on the screen prevents the clips from falling below a horizontal position. 75

When it is desired to use the frame A and its supporting bottom as a stretcher, this can be done by removing the bolts a' from each of the clamps and the clamps removed from 80 the frame. In this case, the stretcher is freed from all parts connected with the wheels so that in carrying the stretcher no weight will be carried, other than the weight of the frame. 85

The canopy can be used with the stretcher or removed therefrom as desired.

I propose to attach to one of the bars A', a box A^x which may be used to hold bandages and other parts of a "first-aid-to-the-injured" outfit. 90

What I claim and desire to secure by Letters Patent is:—

1. A wheeled vehicle comprising a litter or stretcher, a two wheel construction for 95 supporting and transporting the same, and leg supports for the said litter or stretcher, said device including means for securing the wheeled construction to the said stretcher and entirely removing it therefrom, said 100 means also connecting the leg supports to or disconnecting them from the said litter or stretcher, substantially as described.

2. A wheeled vehicle comprising a stretcher frame, a frame carrying two wheels and 105 means for attaching and detaching said wheel frame to the said stretcher frame, said wheel supporting frame containing means that will permit the same to swing towards the stretcher frame to lower the stretcher 110 frame, substantially as described.

3. A wheeled vehicle, comprising a stretcher, a frame carrying two wheels, means for attaching said wheels and frame to the said stretcher to support and transport the same, and detaching them therefrom, said wheel carrying frame being also provided with legs to support the stretcher, and means for transferring the weight of the 115 stretcher from the wheels to the legs, substantially as described.

4. The combination with a stretcher frame, of a pair of wheels for transporting said stretcher, clamps for attaching said wheels to and detaching them from said 120 stretcher, said wheels and all adjunctive parts being connected to said clamps, substantially as described.

5. The combination with a stretcher frame, of two wheels for transporting said 130

stretcher, supporting legs for the stretcher and clamps for attaching said wheels and legs to said stretcher, and detaching them therefrom, said wheels and all adjunctive parts being connected to said clamps, substantially as described.

6. The combination with a stretcher frame, of two wheels, clamps and adjunctive means to secure the said wheels to said stretcher frame, said means including devices for positioning said wheels in two different positions, and supporting legs for said stretcher, all of said means being connected with said clamps and attached to or detached from said stretcher frame by said clamps, substantially as described.

7. The combination with a stretcher frame, of two wheels and clamps for securing said wheels to said frame, the construction also including an axle for said wheels, a pair of rigid arms and a pair of jointed arms connecting said axle with said clamps, substantially as described.

8. The combination with a stretcher frame, of an axle and wheels, clamps for attaching said wheels to said frame, a pair of rigid arms and a pair of jointed arms connecting said axle and said clamps, and means for bending or flexing said jointed arms, said wheels and other parts being connected to and carried by said clamps, and attachable to or detachable from said frame by attaching or detaching said clamps, substantially as described.

9. The combination with a stretcher frame, of an axle and a pair of wheels, clamps and connections uniting them to said axle, means for causing the axle and wheels to occupy positions at different distances from the said stretcher frame, a pair of pivoted legs or supports on each side of the axle, springs for moving said legs outward to a vertical position, and a means connecting the legs on one side of the axle with those on the other side, and passing beneath the axle so that the rising of the axle permits the springs to move the legs or supports outward and the downward movement of the axle draws them inward from the vertical or operative position, substantially as described.

10. The combination with a stretcher frame, of an axle and wheels, clamps and connections for securing said wheels to said frame, means for positioning the axle at two different distances from the said frame, a pair of legs or supports one on each side of

the axle, springs for moving the said legs or supports to a vertical position, links connecting the pairs of legs or supports, said links passing beneath the said axle and having a pivotal connection or joint near the axle, substantially as described.

11. The combination with a stretcher frame, of an axle and wheels, clamps for attaching said wheels and axle to said frame, a pair of rigid arms connecting said axle to two of said clamps, a pair of jointed arms connecting it to other clamps, and the levers for bending the joints of the jointed arms, substantially as described.

12. The combination with a stretcher frame, of an axle and wheels, clamps for attaching said parts to the said frame, a pair of rigid arms between said axle and two of said clamps, a pair of jointed arms between the axle and other clamps, and levers for bending the jointed arms, said levers being connected to a shaft common to both to insure the simultaneous action of both by force applied to one, substantially as described.

13. The combination with the stretcher frame and the supporting bottom thereof, of the narrow flexible strips separate from the bottom but extending along the sides and ends of the bottom and the arms for supporting the inner edge of said strips above the plane of the bottom, substantially as described.

14. The combination with the stretcher frame, of a canopy composed of rigid side frames, and hinged connecting bars, a water-proof covering and a central longitudinal support for the water-proof cover and means for holding said support on said connecting bars midway between the side frames, substantially as described.

15. The combination with the stretcher frame, of a canopy comprising side frames and folding connecting bars, a water-proof cover and a central longitudinal support for said cover, said support having at one end a rigid and at the other end a sliding connection with the connecting bars, substantially as described.

In testimony whereof I affix my signature, in the presence of two witnesses.

IRONE H. RUSSELL.
